BORE CROWN FOR PERCUSSION DRILLING

Didrik Wilhelm Haglund, Sandviken, and Sven Erik Elström, Stockholm, Sweden, assignors to Sandvikens Jernverks Aktiebolag, Sandviken, Sweden, a joint-stock company of Sweden

Application February 28, 1949, Serial No. 78,832

In Sweden February 28, 1948

9 Claims. (Cl. 255—64)

1

This invention relates to a bore crown for percussion drilling provided with two separate cutting elements of hard metal, i. e. alloys of hard carbides, nitrides, silicides, borides etc. which have been sintered together by means of one or more metals from the iron group.

Percussion borers with hard metal cutting elements as hitherto usually used are provided with a simple chisel edge which is secured to the bore crown and has the shape of a plane disc or the like having a cutting edge and standing edge-wise in a slot of the bore crown. Very good results have been obtained with such cutting elements in most rocks. In cracked rocks and in certain very hard and wearing rocks the results will be poorer. Now, experience has shown that bore crowns with more cutting elements are to be preferred in said rocks and that very good yields are obtained with these multiple-edge crowns. However, in these types of drills at least four surfaces have to be ground. Compared with drills having a simple chisel edge and thus merely two grinding surfaces the re-grinding of the multiple-edge drills is essentially more difficult and since it is not possible with advantage to utilize the same grinding device for both types of drills the multiple-edge drills have not come into a more general use.

The present invention relates to a bore crown for percussion drilling provided with two separate cutting elements made of hard metal and the main object of the invention is to provide such a bore crown which merely need be ground along two surfaces, viz. one surface at each cutting edge, or, more exactly, their outer sides. As the grinding surfaces in this case have the same or approximately the same angles of inclination as the corresponding surfaces of a bore crown with a simple chisel edge one may, with advantage, utilize the same grinding apparatus in both cases, and, the grinding will be carried out equally easy and quick in both types of bore crowns. According to the invention the cutting elements have a mainly plate-like shape and are secured in recesses in the bore crown in such a manner that a broad side of the cutting element will face the centre axis of the bore crown and lie entirely or partly open, exposed or free. Moreover, the broad sides of the cutting elements facing the centre axis of the bore crown preferably form an acute angle to planes extending through and including the centre axis of the bore crown. Preferably, said angles are chosen between 30° and 75°, especially about 45°. It should be noted, however, that the two

angles need not be mutually equal and that in the case of different angles the bore crown will obtain an asymmetrical appearance. Each cutting edge is constituted by one of said broad sides together with one adjacent longitudinal side.

Some embodiments will now be described with reference to the accompanying drawing in which Figure 1 shows one embodiment of the invention in side view,

Figure 2 a plan view thereof,

Figure 3 a side view at 90° to Figure 1,

Figure 4 a perspective view,

Figures 5 and 6 shows a modification of the bore crown in side view and plan view respectively.

Finally, Figure 7 is a cross-section of a part of a bore crown on a larger scale.

It should be noted that similar parts in the several figures are indicated by the same reference characters; in Figures 5 and 6 with the addition of the letter "a".

In the bore crown illustrated in Figures 1-4 two cutting elements 1 and 2 of hard metal have a substantially plate-like shape of rectangular or parallel-trapezoid cross-section. The elements are secured in slots or recesses 3 and 4 in a drill head 23. The two recesses form seats for the cutting elements and are preferably disposed at an angle to one another and they have a shape corresponding to the cutting elements; thus the two recesses form together a recess having opposite diverging faces 5, 6 forming an obtuse angle at 5, 6. In the embodiment shown in Figure 5 the corresponding abutments of the recesses 3a, 4a may be rounded or form pockets at 7, 8; but, of course, any other suitable shape may be chosen. Preferably, as shown in Figure 7, the width B of each cutting element (1b, 2b) is essentially greater than its height H. The cutting element need not necessarily have parallel or generally parallel sides but also cutting elements shaped in some other manner may be used. Moreover, the cutting elements need not be undivided but also divided cutting elements may be used.

Each cutting element 1, 2 has an outer longitudinal narrow side 9, 10 and an inner longitudinal broad side 11, 12 respectively, the cutting edge 13, 14 being formed between the outer and inner sides of each element. The inner broad side 11, 12 of the latter faces the centre axis of the bore crown (indicated at A in Figure 7) and is open or exposed, that is free, towards said centre axis, and inclines to the centre axis A at

55

a suitable angle α (Figure 7), preferably at an acute angle ranging from 30° to 70° . The opposite sides of the cutting elements rest directly against the inclined recesses. The elements 1, 2 are spaced apart by a free surface 21 at the centre portion of the bore crown.

During the grinding operation it is merely necessary to grind the outer sides 9, 10 which lie entirely open or exposed and farther away from the centre axis A and are narrower than the inner sides 11, 12, which, as aforesaid, lie entirely or partly open or exposed. In Figure 7 the planes a—a, b—b, c—c, d—d indicate the new surfaces of the cutting element beyond the initial cutting surface 2e and the adjacent surface of the bore crown after regrinding. It is clearly seen that practically the entire cutting elements 1b, 2b may be utilized by such successive regrindings according as the cutting elements are worn out. The inner end surface or edge 2d abuts the inner end of each recess, while the greater flat side 2c lies in each inclined recess.

In order to get a convex shape of the cutting edges 13, 14, which usually is desired, the outer surfaces 9, 10 are ground slightly curved (Figure 2). The edge angle or tool angle (that is the angle between the sides 9, 11 and 10, 12 respectively) may either be equal for all parts of the cutting elements 1, 2 (Figures 1 and 2) or it may be greater at the outer ends of the cutting edge 13a, 14a than at the centre portion thereof (Figure 6), the intermediate portions of the cutting edge passing through a smooth transition from one edge angle to the other. The purpose of having greater edge angles or tool angles at the outer ends than at the centre part of the cutting element is mainly to comply with the desideratum of obtaining great resistance at the outer parts of the cutting element which during drilling are exposed to the greatest stresses.

The end surfaces 15, 16 of the cutting elements (Figures 2 and 4) at the periphery of the bore crown normally form an acute angle to the inner sides 11, 12 of the cutting elements. According to the embodiment in Figure 4 the outer portions of these parts have been ground off so that the sides 11a, 12a pass into the end surfaces through a smooth rounding. In this manner it may be possible to diminish the danger of cracks developing in the cutting elements which could occur due to said acute angles.

Between the cutting elements 1, 2 there may be cut grooves 17, 18 in drill head 23a at the periphery of the bore crown in axial direction for the purpose of discharging boring dust which is collected between the cutting elements. One or more channels 19 (Figures 1-3) for supplying flushing medium to the said grooves or to the bore hole communicate with a centre channel 22 for such medium. Figures 5-7 show a similar centre channel 20 which opens at the surface 21a between the cutting elements 1a, 2a.

The invention is not restricted to the embodiments illustrated on the drawings but includes any device within the frame of the appended claims.

We claim:

1. A rock drill or boring crown for percussion drilling including a drill head having a pair of inclined recesses diverging forwardly and disposed symmetrically with respect to the central axis at the working end of the drill head, each recess forming a seat for receiving and supporting a cutting element; and a pair of substantially flat plate-like cutting elements of substan-

tially rectangular cross section, each having two relatively greater opposite sides of greater width than height and four narrow sides or edges, the cutting elements being individually mounted on the drill head with one of the relatively greater sides of each cutting element fitting in one of the recesses and the opposite relatively greater side of the cutting elements facing said central axis of said drill head in at least partly exposed open positions.

2. A rock drill or boring crown for percussion drilling including a drill head having a pair of inclined recesses diverging forwardly and disposed symmetrically with respect to the central axis at the working end of the drill head, each recess forming a seat for receiving and supporting a cutting element; and a pair of substantially flat plate-like cutting elements of substantially rectangular cross section, each having two relatively greater opposite sides of greater width than height and four narrow sides or edges, the cutting elements being individually mounted on the drill head with one of the relatively greater sides of each cutting element fitting in one of the recesses and the opposite relatively greater side of the cutting elements facing said central axis of said drill head in at least partly exposed open positions, and the narrow side or edge of each cutting element remote from the other cutting element and the central axis of the drill head being fully free and accessible for regrinding in such fashion that the regrinding of said narrow side or edge alone suffices for resharpening of the cutting element involved.

3. A rock drill or boring crown for percussion drilling including a drill head having a pair of inclined recesses diverging forwardly and disposed symmetrically with respect to the central axis at the working end of the drill head, each recess forming a seat for receiving and supporting a cutting element; and a pair of substantially flat plate-like cutting elements of substantially rectangular cross section, each having two relatively greater opposite sides of greater width than height and four narrow sides or edges, the cutting elements being individually mounted on the drill head with one of the relatively greater sides of each cutting element fitting in one of the recesses and the opposite relatively greater side of the cutting elements facing said central axis of said drill head in at least partly exposed open positions, and the narrow side or edge of each cutting element remote from the other cutting element and the central axis of the drill head being fully free and convexly curved along said narrow edge to provide a forwardly projecting convex cutting edge upon each cutting element.

4. A rock drilling or boring crown for percussion drilling including a drill head having at its front end a recess formed with two opposite outwardly diverging faces, each of said faces constituting a support for a cutting element; and a pair of elongated flat plate-like cutting elements each having two opposite elongated plate faces and a plurality of elongated narrow edge faces connecting said plate faces, each of said cutting elements being individually mounted on said drill head with one of said elongated narrow edge faces located at an outwardly located edge of said recess so as to be adapted to be ground, and with one of the plate faces thereof abutting against and supported by one of said opposite faces of said recess, said cutting ele-

ments facing each other with the other plate faces.

5. A rock drill or boring crown for percussion drilling including a drill head having at its front end a recess formed with two opposite outwardly diverging faces, each of said faces constituting a support for a cutting element, each of said recess faces being formed with an abutment in the region of the apex of said recess projecting into said recess transversely to the associated face; and a pair of elongated flat plate-like cutting elements each having two opposite elongated plate faces and a plurality of elongated narrow edge faces connecting said plate faces, each of said cutting elements being individually mounted on said drill head with one of said elongated narrow edge faces located at an outwardly located edge of said recess so as to be adapted to be ground, and with one of the plate faces thereof abutting against and supported by one of said opposite faces of said recess, said cutting elements facing each other with the other plate faces, at least one of said elongated edge faces of each cutting elements abutting against and supported by one of said abutments.

6. A rock drill or boring crown for percussion drilling including a drill head having at its front end a recess formed with two opposite outwardly diverging faces disposed at an acute angle to each other ranging from 30° to 75°, each of said faces constituting a support for a cutting element, each of said recess faces being formed with an abutment in the region of the apex of said recess projecting into said recess transversely to the associated face; and a pair of elongated flat plate-like cutting elements each having two opposite elongated plate faces and a plurality of elongated narrow edge faces connecting said plate faces, each of said cutting elements being individually mounted on said drill head with one of said elongated narrow edge faces located at an outwardly located edge of said recess so as to be adapted to be ground, and with one of the plate faces thereof abutting against and supported by one of said opposite faces of said recess, said cutting elements facing each other with the other plate faces, at least one of said elongated edge faces of each cutting elements abutting against and supported by one of said abutments.

7. A rock drill or boring crown for percussion drilling including a drill head having at its front end a recess formed with two opposite outwardly diverging faces, each of said faces constituting a support for a cutting element, each of said recess faces being formed with an abutment in the region of the apex of said recess projecting into said recess transversely to the associated face, said drill head having at least one lateral groove extending in axial direction of said drill head from the apex of said recess and adapted to receive drilling dust, said drill head also having an internal passage ending in said groove and adapted for supplying a flushing fluid to the front end of said drill head; and a pair of elongated flat plate-like cutting elements each having two opposite elongated plate faces and a plurality of elongated narrow edge faces connecting said plate faces, each of said cutting elements being individually mounted on said drill

head with one of said elongated narrow edge faces located at an outwardly located edge of said recess so as to be adapted to be ground, and with one of the plate faces thereof abutting against and supported by one of said opposite faces of said recess, said cutting elements facing each other with the other plate faces, at least one of said elongated edge faces of each cutting elements abutting against and supported by one of said abutments.

8. A rock drilling or boring crown for percussion drilling including a drill head having at its front end a recess formed with two opposite outwardly diverging faces, each of said faces constituting a support for a cutting element; and a pair of elongated flat plate-like cutting elements each having two opposite elongated plate faces and a plurality of elongated narrow edge faces connecting said plate faces, each of said cutting elements being individually mounted on said drill head with one of said elongated narrow edge faces being curved and located at an outwardly located edge of said recess so as to be adapted to be ground, and with one of the plate faces thereof abutting against and supported by one of said opposite faces of said recess, said cutting elements facing each other with the other plate faces.

9. A rock drilling or boring crown for percussion drilling including a drill head having at its front end a recess formed with two opposite outwardly diverging faces, each of said faces constituting a support for a cutting element; and a pair of elongated flat plate-like cutting elements each having two opposite elongated plate faces and a plurality of elongated narrow edge faces connecting said plate faces, each of said cutting elements being individually mounted on said drill head with one of said elongated narrow edge faces being curved and located at an outwardly located edge of said recess so as to be adapted to be ground, and with one of the plate faces thereof abutting against and supported by one of said opposite faces of said recess, said cutting elements facing each other with the other plate faces and having cutting edges formed by said other plate face and by said outwardly located narrow edge face of each cutting element, the angle of the cutting edge of each cutting element being greater at the periphery of the drill head than at the central portion of the cutting edge.
